SHIFTING POST BINDER,
FILED JUNE 18, 1921.

3 SHEETS-SHEET 3

UNITED STATES PATENT OFFICE.

ARTHUR R. MEYER AND ELMER A. REED, OF CHICAGO, ILLINOIS, ASSIGNEES TO
WILSON-JONES LOOSE LEAF COMPANY, A CORPORATION OF ILLINOIS.

SHIFTING-POST BINDER.

Application filed June 18, 1921. Serial No. 478,489.

To all whom it may concern:

Be it known that we, ARTHUR R. MEYER and ELMER A. REED, citizens of the United States, and residents of the city of Chicago, in the county of Cook and State of Illinois, have invented certain new and useful Improvements in a Shifting-Post Binder; and we do hereby declare that the following is a full, clear, and exact description of the same, reference being had to the accompanying drawings, and to the numerals of reference marked thereon, which form a part of this specification.

This invention relates to loose-leaf binders in which a loose-leaf can be readily inserted or removed, and in which the leaves are locked by longitudinally shiftable leaf-holding means as disclosed in our co-pending application Serial No. 478,488, filed June 18, 1921, of which this invention is an improvement.

It is an object of this invention to provide releasable shifting means in combination with the shiftable leaf-holding means for the purpose of shifting the same.

It is a further object to provide such means as can be associated with the movable elements for opening and closing the binder without in any way interfering with the operation thereof and in which the binder must be fully expanded to unlock the leaves.

With these and others objects in view which will become more apparent in the following description and disclosures in the drawings, our invention comprises the novel features of construction, combinations and arrangements of parts hereinafter described and more specifically pointed out in the appended claims.

In the accompanying drawings which illustrate certain preferred embodiments of our invention and in which similar reference characters refer to similar features in the different views:

Figure 1 is a front plan view of a binder in which the shiftable posts are in unlocking position.

Figure 2 is a fragmentary front plan view on an enlarged scale of one end of the binder with parts broken away.

Figure 3 is a fragmentary section on the line 3—3 of Figure 1.

Figure 4 is a fragmentary plan view of a portion of the binder illustrating the loose leaves in unlocked position.

Figure 5 is a fragmentary sectional view through one side wall of the binder illustrating the slidably supported leaf-holding posts.

Figure 6 is a section on the line 6—6 of Figure 1 on a slightly enlarged scale.

Figure 7 is an elevational view of a leaf-holding post provided with shifting means.

Figure 8 is a section on the line 8—8 of Figure 6.

Figure 9 is a fragmentary plan view partly in section of the post-shifting means.

Figure 10 is a view similar to Figure 1 illustrating a modified form of post-shifting means.

Figure 11 is a section on the line 11—11 of Figure 10 on a slightly enlarged scale.

Figure 12 is a fragmentary section on a slightly enlarged scale on the line 12—12 of Figure 10.

As shown in the drawings:

In the accompanying drawings, we have illustrated a loose leaf binder which may be of any suitable construction to which our invention is applied. The form of binder shown has side walls 1, portions of which are bowed outwardly, and horizontal flanges 2 slidably beneath end plates 3 which in turn support the curved base or back 4 of the binder by bolts or the like which extend through journal blocks 5. The blocks 5 rotatably support the screw element 6 provided with reversely threaded sections upon which shiftable elements or nuts are mounted which are connected by links 7 to the side walls 1 of the binder. By rotating said screw element and shifting the nuts, the sides of the binder are brought together or further separated during the operation of what is termed closing or opening the binder.

The leaf-holding means which are posts in the present illustrated instance are supported on slidable plate members 8 which are supported at a proper height on the inner sides of side walls by means of headed studs or bolts 9, the shanks of which operate in slots 10 (see Figure 5) in the side walls of the binder with the heads overlying the slots on the outer surface of said walls. The plate members 8 are arranged in pairs, one pair comprising opposite plates on the side walls. A simple construction consists in using two pairs of plate members spaced a

proper distance apart at the transverse central plane of the binder, and each pair may support one or more pairs of leaf-holding posts 11 and 12 which telescope one in the other, each pair being thereby united by the posts supported thereby constitutes what we term a leaf-holding unit and as there are two pair of plate members in the present construction, there will be two adjustable or shiftable leaf-holding units. The structure of these leaf-holding units, however, forms no part of this invention except in so far as it cooperates therewith.

The structure of the present invention relates more directly to releasable means for shifting said units, being characterized by the fact that said means become disengaged from effective operative relation with said units at certain stages. Referring now to Figures 1 to 9 which illustrate the first form of our invention, it will be noted that the shiftable elements or nuts 13 on the screw element 6 are of special construction, being provided with latching grooves 14 for receiving the power arms 15 of shifting levers 16 pivotally mounted upon the brackets 17, extending inwardly from the plates 3. The lever arms 18 of the shifting levers 16 have inclined ends which enter slots 19 in abutments or plate members 20 depending from the end posts 12. Each leaf-holding unit has, therefore, an abutment. The forward ends of said lever arms 18 are provided with lugs 21 (see Figures 3 and 8) which bear against the outer sides of the plates 20 adjacent said slots 19 during one direction of movement thereof.

On the opposite sides of said abutments 20, said lever arms 18 are provided with raised lugs or ridges 22 (see Figure 9) which bear against the abutments 20 during a movement of said levers in a direction opposite to the aforementioned movement thereof. In the positions illustrated in Figures 1 and 2, the leaf-holding posts are in unlocking position with respect to the mushroom slots of the leaves 23 as shown in Figure 4 and the sides of the binder are fully expanded. If the screw element 6 is now rotated to shift the nuts 13 inwardly, the levers 16 will be oscillated on the pivots, the lugs 22 engaging the abutments 20 and shifting the same together with the posts 12 and plate members 8 outwardly until the studs 9 reach the opposite or outer ends of the slots 10 which is the locking position thereof and at which point the power arms 15 can be carried out or disengaged from the grooves 14 as shown in Figure 9, so that the nuts 13 can continue to be shifted inwardly to completely close the binder. When it is desired to open the binder and bring the posts to unlocking position again, the screw element 6 is rotated in the opposite direction 65 to shift the shiftable elements or nuts 13

outwardly. As the inner walls of grooves 14 are higher or longer than the outer walls, the power arms 15 of the levers 16 will be struck by these higher walls which are provided with camming surfaces to cam said power arms into the grooves 14, at which time the lever arms 18 will be forced to swing or oscillate inwardly, the lugs 21 engaging the said abutments 20, shifting the same together with the posts 12 and plate members 8 inwardly until the studs 9 reach the opposite or inner ends of the slots 10 which is the unlocking position of said posts and the limit of the outward movement of the nuts 13. Accordingly, the leaf-holding posts cannot be brought to unlocking position until the binder has been fully expanded or open as shown in Figures 1 and 2 so that leaves cannot be inserted or removed before the binder has been fully opened, preventing tearing or mutilating of the same by one who is indifferent to completely opening the binder for the insertion or removal of leaves.

It is characteristic of the levers 16 that they are oscillated backwards and forward for shifting the leaf-holding units and that they are disengageable from the shiftable elements 13 when the units are in locking position. For these reasons we may term the levers 16, "oscillatable and disengageable" shifting devices that engage the abutments 20 on the posts 12 for shifting said units.

In the second form of our invention as illustrated in Figures 10 to 12, oscillatable lever devices 23 are attached to the shiftable elements 24 for shifting the leaf-holding units, and as the structures thereof are similar, only one has been illustrated in detail and need be described. With reference to Figure 12, it will be noted that each lever device 23 consists of a segmental-shaped member pivoted at its lower end to the side of a nut 24 on the screw element 6, and provided upon its upper edge with spaced lugs 25 with an arcuate surface between said lugs, each end post 12 and therefore each leaf-holding unit being provided with a downwardly projecting abutment 26 resting upon the arcuate surface between said lugs 25. In order to hold either lug in engagement with an abutment 26, a yielding means has been provided, and as shown, the same comprises a plate spring 27 secured at one end to the side of the nut 24 adjacent its lever device 23 and being provided with a bead 28 forming oppositely-directed shoulders against which a pin 29 on the lever device 23 bears when said device is in either of its operative positions 125 to prevent the device from snapping or shifting over to the opposite side. The spring 27 should hence be sufficiently strong to overcome the force required to shift the units. In the drawings, the posts 11 and 12 are 130

shown in unlocking position with respect to the entrance neck of the slots in the leaves and the binder is substantially fully expanded. In order to shift the posts to locking position, it is first necessary to rotate the screw element 6 so as to shift the nuts 24 a little further outwardly, causing the devices 23 to trip or snap over to the opposite sides with the other lugs 25 coming into engagement with the abutments 26. This operation is possible because the posts 12 and abutments 26 are at their outer limits of movement, since the pins 9 are at the outer ends of the slots 10 at this time. By rotating the screw element 6 in the opposite direction now, the shiftable elements or nuts 24 will move inwardly carrying the leaf-holding units inwardly to locking position with respect to the slots in the loose leaves. When said units have been shifted to the inward limits of their movement as defined by the inner ends of the slots 10, the devices 23 will be snapped or tripped over the beads 28 of springs 27 to the opposite side allowing the nuts or shiftable elements 24 to ride from under the abutments 26 to completely close the binder. Thus at the locking position of the leaf-holding units, the lever devices 23 and shiftable elements 24 become disengaged from the abutments 26 and leaf-holding units. When the binder is again opened, the shiftable elements 24 will travel outwardly and when they reach the abutments 26, the inner lugs 25 will be in position to engage said abutments, the lever devices 23 being at that time in the position illustrated in Figure 12 in which position the outer lugs 25 can pass under the abutments 26.

From the foregoing, it is evident that the leaf-holding units of this second form of invention are not brought to unlocking position until the binder has been fully expanded just as in the first form. It is also characteristic of the second form that the shiftable elements 24 become disengaged from operative relation with the abutments 26 when traveling inwardly from the locking position of said leaf-holding units. It should also be noted that the shouldered beads 28 of the springs 27 cooperating with the pin 29 constitute yieldable fulcrums for the devices 23, thereby producing a leverage action, and that the lever devices 23 are oscillated on their pivots to bring them into effective engagement with said abutments 26 during the backward and forward shifting movements of the shiftable elements 24.

It is characteristic of this invention that when using equally spaced posts, the leaves can be readily offset as described in our said co-pending application, adapting the binder both for pen and ink or mechanical book-keeping.

We are aware that numerous details of construction can be varied through a wide

range without departing from the principles of this invention, and we therefore do not purpose limiting the patent granted otherwise than necessitated by the prior art.

We claim as our invention:

1. In a loose leaf binder having slidably mounted leaf-holding units, the combination with the shiftable elements for opening and closing said binder, of abutments on said leaf-holding units, and lever devices engaging said abutments and operable by said shiftable elements for shifting said units. 70

2. In a loose leaf binder having adjustably mounted leaf-holding units, each unit being provided with an abutment, oscillatable lever devices for contacting against said abutments, and means for shifting said devices. 80

3. In a loose leaf binder, a plurality of adjustable leaf-holding units, each having a downwardly extending abutment, oscillatable devices having projecting lugs for engaging said abutments, and means for operating said devices to bring said lugs into engagement with said abutments for shifting said units. 85

4. In a loose leaf binder, the combination with the shifting elements for opening and closing the binder, of adjustably mounted leaf-holding units, each unit having a downwardly extending abutment, oscillatable devices for engaging opposite sides of said abutments, and means operable by said shiftable elements for shifting said devices. 95

5. In a loose leaf binder having shiftable elements connected to the sides thereof for expanding and contracting said binder, the combination with a loose leaf having a plurality of slots, a plurality of leaf-holding units engageable in said slots and shiftable to locking and unlocking position with respect thereto, and means operable by said shiftable elements for shifting said units to unlocking position at the end of the maximum expanding movements of said elements. 100

6. In a loose leaf binder having shiftable elements connected to the sides thereof with means for supporting and operating said elements for expanding and contracting said binder, a plurality of shiftable leaf-holding units, and means engageable and disengageable with said elements for shifting said units. 115

7. In a loose leaf binder having shiftable elements connected to the sides thereof with means for supporting and operating said elements for opening and closing said binder, a plurality of shiftable leaf-holding units, each having an abutment and a pivoted device cooperating with each abutment and having lugs engageable with opposite sides thereof, said pivoted devices being operated against said abutments by said shiftable elements to bring said units into leaf unlock- 120

125

130

- ing position at the limit of adjustment of said elements for maximum expansion of said binder.
8. In a loose leaf binder having shiftable elements connected to the sides thereof with means for supporting and operating said elements for opening and closing the binder, a shiftable leaf-holding unit having a depending abutment adjacent one of said shiftable elements, and a pivoted lever device having an arm engageable with opposite sides of said abutment, and a second arm adapted to be operated by said adjacent shiftable element.
- 15 9. In a loose leaf binder, the combination with a shiftable element for expanding the binder, said element having a cam notch, a shiftable leaf-holding unit having a depending abutment adjacent said element, and a pivoted lever having an arm engageable with opposite sides of said abutment, and an arm engageable with said cam notch for operation by said element.

10. In a loose leaf binder, the combination with a shiftable element for expanding the binder, a shiftable leaf-holding unit having a depending abutment, and a lever device adapted for engaging said abutment and engageable and disengageable with said element.

11. In a loose leaf binder, the combination with a shiftable element for expanding the binder, a shiftable leaf-holding unit, and an operating device adapted for effecting a connection between said unit and element for shifting said unit at the maximum expanding movement of said element.

In testimony whereof we have hereunto subscribed our names in the presence of two subscribing witnesses.
